ORNAMENTAL SHUTTER

Cyril L. Johnston, Arlington Heights, Ill., assignor to Leslie Building Products, Inc., Franklin Park, Ill., a corporation of Delaware

Filed May 29, 1969, Ser. No. 17,414

Term of patent 14 years

Int. Cl. D25—02

U.S. Cl. D13—1

FIG. 1 is a front elevational view of my new design for an ornamental shutter;

FIG. 2 is an enlarged perspective view of my new design for an ornamental shutter partially broken away so as to show upper and lower corner portions and vertical and horizontal cross-sectional configurations of the ornamental shutter in greater detail; and

FIG. 3 is a perspective view of my new design for an ornamental shutter partially broken away and showing upper and lower end portions of the ornamental shutter in greater detail.

I claim:

The ornamental design for an ornamental shutter, substantially as shown.
